TRAIN CONTROL SYSTEM

Lester L. Jones, Oradell, N. J.

Application October 23, 1926. Serial No. 143,608

71 Claims. (Cl. 246—63)

This invention relates to train control systems, and has special reference to the provision of an improved train control system of the induction type.

5 A prime desideratum of my present invention relates to the provision of a train control system of the induction type embodying cooperating vehicle carried and roadside inductors in which an activating condition may be produced in the
 10 vehicle carried inductor to effect some active operation of the train control apparatus by the movement or positioning of said vehicle carried inductor relatively to a roadside inductor employing circuit means devoid of an energy source.
 15 In prior induction train control systems of which I am aware, the activating operation of the vehicle carried circuits was produced by the transmission of an activating or energizing influence from the roadside inductor to the vehicle carried inductor
 20 obtained by energizing the roadside inductor either directly by means of a source of energy located on the roadside or indirectly by locating the source of energy on the moving vehicle and reflexing or retransferring said energy through
 25 cooperating vehicle carried and roadside inductors from the vehicle to and through the roadside inductors and back to the vehicle apparatus. By my present invention I propose to eliminate the principal objections to these systems of prior design, which objections have their origin either in the necessity of using roadside energy for the roadside inductors or in the necessity of using a multiplicity of inductors for reflexing energy where the source of energy is located on the
 30 vehicle.
 35

A corollary prime object of my present invention relates to the provision of an improved induction train control system in which a single roadside inductor may be employed and selectively operated to produce in a vehicle carried inductor means a number of operations corresponding to the conditions of the roadside, which operations comprise the production of a condition in the vehicle carried inductor means to produce a tripping or train control stopping operation in the train control apparatus or/and a condition in the vehicle carried inductor means to permit a passive state in the vehicle carried apparatus, that is, to permit the vehicle to pass a
 40 roadside controlling station without any operation being produced in the vehicle carried apparatus combined with a third condition producible in the vehicle carried inductor means for effecting a resetting operation of the vehicle carried apparatus in response, for example, to a "clear" or
 45
 50
 55

"caution" roadside condition. A further prime object of my present invention relates to the provision of an induction system of this character capable of producing the "clear" or "caution" operating conditions in the vehicle carried apparatus by means of a roadside inductor devoid of a source of energy, the results attained being therefore capable of being produced with the use of a single inductor controlled by circuit means devoid of a roadside energy source.

60 Other principal objects of my invention will become evident as the description proceeds, and to the accomplishment of the foregoing and such other objects as will hereinafter appear, my invention consists in the elements and their relation 65 one to the other in circuit combinations as hereinafter more particularly described and sought to be defined in the claims; reference being had to the accompanying drawings which show the preferred embodiment of my invention, 70 and in which:

75 Fig. 1 is a wiring diagrammatic view of a train control system embodying the principles of my invention and showing the cooperation between the vehicle carried and roadside inductors 80 for producing the train control operations, and

Fig. 2 is a wiring diagrammatic view of the circuits immediately controlling and being controlled by the cooperative vehicle carried and roadside inductors, more specifically depicting 85 the physical relations between the circuits and the principles employed therein.

90 Referring now more in detail to the drawings, I will make reference first to Fig. 2 thereof to explain the elements, the combination of elements and the underlying principles of a train control system embodying my invention, after which I will have reference to Fig. 1 of the drawings and describe the use of the combined elements in association with train control circuits 95 for producing the train control operations.

95 Referring therefore first to Fig. 2 of the drawings, the vehicle carried and roadside inductors comprise respectively a vehicle carried inductor means generally designated as A and a track inductor generally designated as B over which the vehicle inductor is movable in the movement of the vehicle over the roadside, the said vehicle inductor A comprising inductively coupled primary and secondary coils p and s respectively, both 100 preferably wound on laminated cores 10 and 11 respectively and having a relation such as is described and claimed in the copending application of A. G. Shaver, Serial No. 506,595, filed Oct. 10, 1921. The primary coil p is connected to an 105 110

alternating current source of energy 13 designated as "360~" by means of a primary circuit *a* which is generally designated in Fig. 2 of the drawings by the legend "Primary", the said 5 primary coil *p* preferably including a second winding 14 wound over the core of the secondary coil *s* in opposite sense thereto, the said winding 14 constituting a buckdown winding for producing a neutralization of residual flux in the secondary coil *s* under certain conditions of operation, as is described and claimed in the patent 10 to A. G. Shaver 1,521,332 of December 30, 1924. The track inductor *B* comprises a track coil *t* also preferably wound over a laminated core 15 and a circuit *b* of which the track coil *t* preferably forms a part, the said circuit *b* being devoid of any energy source.

As is described in the aforementioned copending applications, as well as in the patent to A. G. Shaver No. 1,521,332 for Shunting or trip device, 20 patented Dec. 30, 1924, when the vehicle transformer inductor *A* covers an inert track element such as *B*, that is, such a track element in open circuit, the magnetic flux flows from the primary 25 coil *p* to and through the inert track element, resulting in a diverting or shunting of magnetic flux from the secondary coil *s*, the shunting of the said secondary or receiving coil *s* resulting in a reduction in the energizing current of a relay 30 16 or equivalent device designated in Fig. 2 by the legend "Trip relay" located in a secondary circuit *c* of which the secondary coil *s* forms a part and resulting in a consequent effective de- 35 energization of the device 16, with the result that any apparatus such as the armatures controlled thereby are opened for tripping other train control circuits. It will be understood that normally, that is, when the vehicle carried inductor *A* is not in position over the track inductor *B*, the transference of flux from the primary coil *p* to the secondary coil *s* of the vehicle inductor *A* energizes the device 16 in the 40 secondary circuit *c*.

I have discovered that when the engine or vehicle carried inductor *A* moves or is positioned over a track inductor such as *B*, either inert or provided with a circuit *b* short-circuited or tuned, that not only does the power supplied by the alternating current source of energy 13 to the primary coil *p* of the vehicle carried inductor change, but that marked changes are produced in the phase angle between the current and voltage effective on said primary inductor coil. I have further found that these produced phase 45 changes may be effectively applied in operating controlling circuits on the vehicle and in producing activating operations thereof by means of such short-circuited or tuned track inductor circuit without the use of any roadside energy source. I have empirically determined that such 50 controlling circuits may be very effectively governed by the employment of a relay 12 designated in Fig. 2 by the legend "Reset relay" located in the primary circuit *a*, the said relay being a two-element relay having its elements 55 so disposed in the primary circuit as to efficiently respond to the phase changes as well as the power change produced in the vehicle carried inductor in the cooperation of the latter with the roadside inductor circuit. This reset relay 60 comprises in the preferred construction armature and field coils 17 and 18 designated by the legends "Armature" and "Field" in Fig. 2, the field coil being preferably arranged in series with 65 and the armature coil being preferably arranged

in parallel to the primary coil *p* of the vehicle carried inductor.

I have found that the constants of the armature and field circuits may be so selected as to produce a no relay torque for some one track condition and positive or negative torques of different magnitudes for other track conditions. More specifically, I have determined that the resistance and reactance of the vehicle carried primary inductor *p* may be so related to the relay 80 armature circuit reactance and resistance as to produce the desired results. For each track condition the impedance of the primary inductor *p* may be represented by resistance and reactance factors, the reactance factor being usually though not necessarily inductive; and both resistance and reactance factors vary markedly depending upon the track condition. For the condition of no torque in the relay, I have determined that the quotient of the resistance and the reactance 85 of the primary inductor should equal the quotient of the armature circuit reactance divided by the resistance, this being mathematically represented as:

$$R = \frac{1/\omega C}{\omega L} R_p$$

where

R=The primary inductor resistance

ωL=The primary inductor reactance

1/ωC=The relay armature circuit reactance and

R_p=The relay armature circuit resistance

Slight corrections to this are necessary for 110 the relay armature inductive reactances, and for small voltages which may be induced in the relay armature coil from its field.

To produce the desired constants, the armature 17 of the relay 12 is connected across the current 115 supply source through suitable resistance and capacitance produced by a resistor *R_p* and a condenser *C* arranged in the in-parallel circuit of the armature 17, these being the resistance and 120 capacity factors embodied in the foregoing equation.

Normally with this circuit arrangement described and with the preferred selected constants thereof, the currents in the armature and field 125 17 and 18 of the relay 12 are phased 90 electrical degrees apart, producing a no torque condition in the relay so that an armature element 19 controlled by the armature coil 17 is held in a neutral position as shown in Fig. 2 of the drawings. However, when the vehicle carried inductor *A* 130 moves over the track inductor *B* with the track side circuit *b* short-circuited or tuned in a manner to be described presently, the change in the power supplied to the primary coil *p*, together with the shift in the phase angle between the 135 current and voltage effective thereon, produces a marked shift in the phase between the armature and field currents of the relay 12 producing a change in the relay torque from no torque to either a positive or negative torque of different 140 magnitudes, depending upon the characteristic of the roadside circuit *b*. The phase shift and power change are different when the vehicle carried inductor is in cooperation with a short-circuited track inductor than when it is in cooperation 145 with a tuned track inductor, and hence it becomes possible to discriminate between the effects on the relay 12 in accordance with different conditions, as for example "clear" or "caution" 150 roadside conditions. The number of indications

produced in the relay 16 may be further extended by tuning the track circuit to values above or below resonance so as to produce sharp changes in the vehicle carried inductor primary currents 5 lagging or leading the applied primary voltage. These changes may be made more critical or pronounced by tuning the engine power supply circuit as by means of a series condenser 20 arranged in the primary circuit *a* and designated in Fig. 2 10 by the legend "Supply circuit tuning or power factor changer".

To produce a variety of indications in the vehicle carried inductor system as described, the track inductor circuit *b* comprises a movable contact 21 movable over a series of taps 22, 23, 24 and 25, movement of the contact 21 on the tap 22 producing a short-circuited inductor circuit, movement of the contact 21 on the tap 23 introducing a capacity in the circuit *b* by means of 15 the condenser 26 and movement of the contact 21 on the tap 24 introducing a different condenser 27 in said circuit *b*. The condensers 26 and 27 may be of the desired values to either tune the circuit *b* to resonance to the frequency 20 of the vehicle carried alternating source 13, or circuit *b* may be tuned above or below such resonance point to produce the lagging or leading primary currents described. As applied to the vehicle carried circuit shown in Fig. 2, I may 25 merely employ the taps 24 and 25 or said taps 24 and 25 in combination with the tap 22, the tap 25 being employed to open the track circuit *b* to produce a deenergizing operation of the vehicle carried relay 16, the tap 22 or 24 being 30 employable for permitting the vehicle carried apparatus to move over the roadside apparatus without change and the tap 24 being employable for introducing the tuned trackside circuit to produce an activating condition in the vehicle 35 inductor *A* to operate the relay 12 from the no torque to the maximum torque position, these operations corresponding respectively to "danger" position, to a "clear" passive position and to a "clear" active or resetting position.

40 45 To produce the most efficient results, the constants and the characteristics of the circuits must be suitably selected and determined, and I have found that the following considerations are of importance.

50 55 The torque operating the relay 12 is related to the phase angle change between current and voltage in the engine primary inductor as well as the percentage change of power input into the primary of the vehicle carried inductor due to the cooperation of the same with the tuned track inductor. It will be apparent that where the normal power input is a minimum and the power abstracted by the track tuned circuit is a maximum, the percentage change of power is greatest.

60 65 The A. C. supply circuit 13 should have considerable inductance both for the magnetic field of the engine inductor and for the field of the reset relay, this inductance at 360 cycles giving considerable reactance to the generator or primary circuit. A phase compensator is therefore desirable in this A. C. supply circuit to facilitate the introduction of sufficient power to the engine inductor. Without such a phase compensator the generator E. M. F. would be greater, thus requiring a larger A. C. generator. For this purpose, therefore, the tuning condenser 20 heretofore referred to is supplied, and this condenser is adjusted to approximately neutralize the inductive reactance of the primary circuit, thus permitting the flow of a

large magnetizing current with a relatively small driving E. M. F.

In connection with the adjustment of this phase compensating condenser 20, I prefer to set it so that the resonant frequency of the primary circuit *a* is normally somewhat higher than the frequency of the generator or A. C. source 13, this for the purpose of causing the primary circuit *a* to stabilize the speed of the generator. This is important because the proper operation of the reset relay depends upon the coincidence of generator frequency and trackside circuit resonant frequency. Any considerable variation of generator frequency, say of the order of 5% would detune the generator from the trackside circuit resonant frequency and thereby minimize the reaction between track and engine inductors.

The stabilization of the speed of the generator occurs because any increase of generator speed brings the generator frequency closer to the primary circuit frequency, reducing the reactance of the primary circuit, increasing the current flow therein, and thereby the power input to the inductor. This produces an additional load thrown on the generator which tends to reduce its speed. Conversely a tendency towards lower speed on the generator due, for example, to a drop in steam pressure, results in a diminished load on the generator which tends to check the speed reduction. The importance of this frequency relationship 100 between the generator and the primary circuit *a* is emphasized by considering the result of reversing the relation. In the case of making the primary circuit resonant to a frequency lower rather than higher than the generator frequency, 105 low steam pressure would reduce the generator speed, slightly causing an increase in load and thereby a further speed drop, etc.

The secondary circuit *c* is also preferably tuned as by means of a condenser 27 designated by the legend "Tuning condenser" in Fig. 2. The purpose of the tuning of the secondary circuit *c* is primarily to neutralize the inductive reactance of the circuit so as to permit a larger flow of current therein with more magnetic flux to operate the relay 12. The inductance changes of the trip relay circuit due to inductance change in the engine inductor resulting from cooperation with the track inductor are relatively small and contribute little to the drop in the current of the relay 125 16 when passing over an open track inductor. For example, I have found that the engine inductor inductance change is less than 10%. This results in a change of less than 5% in the circuit inductance of the secondary circuit *c* because the 130 efficiency relations demand that the trip relay have approximately the same inductance as its supply source. The secondary circuit frequency change is therefore less than 2½%, and this change could not be relied upon for operating the 135 relay 16, since the normal speed regulation of the supply generator is only of this order of magnitude. Operation of this relay 16 in the secondary circuit therefore depends primarily upon a reduction of the driving E. M. F. in the transformer secondary when passing over an open circuited track inductor.

Now it is important that the normal current of the secondary relay 16 be fairly constant under all normal variations of generator frequency. As 145 described above, the primary current varies with the generator frequency and a corresponding variation of E. M. F. in the secondary circuit *c* results. In order to hold the current in the relay 16 of this circuit approximately constant through 150

- these conditions, I find it preferable to adjust the resonant frequency of the secondary circuit *c* to a value slightly lower than the normal generator frequency. Then when the generator speed drops, 5 causing a reduction of primary current and a lower driving E. M. F. in the secondary circuit *c*, the reactance of the secondary circuit *c* decreases correspondingly due to the nearer approaching of the generator frequency to the frequency of the secondary circuit *c*. This reactance drop tends to neutralize the effect of the drop of induced voltage and thereby maintains the current of the relay 16 more nearly constant. Conversely when the generator overspeeds, the increased primary current causes an increase in secondary 10 E. M. F. No increase of current of the relay 16 results, however, due to the higher reactance of the secondary circuit *c* for this higher generator frequency.
- 15 It will be apparent that the elements of my invention thus far described may be employed singly or in combination. Thus it will be evident that the primary circuit *a* may be employed in combination with the track inductor without the use 20 of the secondary circuit *c* to produce the characteristic operations of the relay 12. It will be further apparent that the physical phenomena occurring by the cooperation of such a primary circuit with the track inductor circuit may be employed for variously operating the train control 25 relays. When the primary circuit *a* is used in combination with the secondary circuit *c* for selectively operating a number of relays, it will be further apparent that various combinations may 30 be produced and various operations effected without departing from the spirit of the invention as defined in the hereinafter appended claims. In applying the invention, therefore, to the train control circuit arrangement about to be described, 35 40 I desire it to be understood that such description is given by way of explanation of one of the preferred ways of employing the principles of the invention, and not by way of limitation.
- In the train control system exemplified, the 45 relay 16 is employed as a trip relay for operating a train control circuit *d* and the relay 12 is employed as a reset relay for operating a train control circuit *e* to reset the operation of the vehicle carried apparatus after the same has been tripped. Where the 50 cooperation of the trip and reset circuits is such as to weaken the trip relay during reset relay operation or any part of the latter, I preferably employ a means for controlling the reset relay 12 to delay the release thereof, it being understood 55 that the normal operation of the reset relay 12 to an activating condition takes place only during the time of cooperation between the vehicle carried inductor *A* and roadside inductor *B*. This means to delay the release of the reset relay carries 60 the condition of the reset relay over any mechanical or electrical transients which may be due to the speed of action required of the parts in high speed train operation or over any valleys in the curve of operation of the track inductor 65 which may be due to a reversal of E. M. F. in the track inductor. The release controlling means may be associated with the reset or trip relays, and in the preferred construction, as shown in Fig. 2, the same is associated with the reset relay 70 12. Preferably this release controlling means comprises a slow release magnet 28 controlling the armature element 19 of the reset relay, the said magnet 28 receiving energy from a D. C. source 75 through a circuit comprising a conductor 30, a 29 slow release controller generally designated as 31;

a conductor 32, magnet 28, conductor 33, contacts 34 normally open but closed when the armature 19 is actuated under reset conditions, and conductor 35.

The slow release controller 31 comprises a vessel 80 having a body of mercury 36 therein, into which extends, in the branch 31' of the vessel 31, a wire heater 37 preferably made of nickel having a contact 38 at the bottom end thereof, the conductor 30 having a lead 30' extending into the mercury body in the other branch 31² of the vessel 31. With this construction when the armature of the reset relay is operated to close the contacts 34 and the magnet 28 is energized to hold the reset relay armature in its actuated position, the closing of the circuit through the slow release controller heats the heater 37, causing an expansion of air in the heater chamber 31' of the vessel which causes the mercury body 36 to move into the air chamber 31² of the vessel 31, such movement after a predetermined time breaking the connection between the mercury body and the heater contact 38, such breaking of connection causing a deenergization of the magnet 28 and a consequent release of the armature reset relay.

Now referring to Fig. 1 of the drawings, I show the controlling circuits of Fig. 2 applied for operating other train control elements to produce the tripping and resetting operations. In Fig. 1 the circuits of Fig. 2 are reproduced by parts bearing 105 similar reference characters, some parts, however, such as the relays 16 and 28 being represented diagrammatically, the reset relay 12 being shown with two field coils 18 on opposite sides of the armature coil 17. The other parts are all 110 similar with the exception that the D. C. energy source 29 is represented by a generator instead of a battery and the contacts 34 are separated into three independent contacts 34', 34² and 34³.

The mechanism or circuits operated by the controlled circuits *d* and *e* are substantially the same as those described and claimed in the copending application of Shaver and Meisel Ser. No. 138,869, filed Oct. 1, 1926, for Train control system; and in the present disclosure I show the manner in 120 which such circuits control the operation of translating relays 40 and 41.

The trip circuit *d* derives its energy from a potentiometer 42 connected to the mains of the generator 29 by means of conductors 43 and 44, 125 the trip circuit being traced from the positive side of potentiometer 42, conductor 45, trip contact 46, conductor 47, a manually operable switch 48, conductor 49 having a first branch through the relay magnet 41 by way of conductors 50 and 51, stick contact 52, and having the second branch through the relay magnet 40 by way of conductors 53 and 54 and stick contact 55, both branches joining in the common conductor 56 and conductor 57 back to a negative point of the potentiometer 42. These relays 40 and 41 are therefore normally energized through the two stick circuits traced and closed at the trip contact 46. When the vehicle carried inductor *A* moves over an open-circuited track inductor *B*, the trip relay 140 16 is effectively deenergized, opening the trip contact 46 resulting in the opening of the stick circuits traced, with the consequent persistent deenergization of the relay magnets 40 and 41. Also when the vehicle carried inductor *A* moves 145 over a short-circuited track inductor *B*, the trip relay contact 46 will be maintained in closed condition unaffected the operation of the relay magnets 40 and 41.

The reset circuit *e* is employed for resetting 150

- the relay magnets 40 and 41 when the reset relay 12 is operated. For operating both magnets 40 and 41, I employ two reset contacts 34' and 34² as hereinabove stated. These reset circuits may 5 be traced from the positive side of energy potentiometer 42, conductor 45, trip contact 46 (closed during the movement of vehicle carried inductor A over a closed or tuned trackside circuit inductor B) conductor 47, manually operable switch 10 48, conductor 49, a first branch going through conductor 50, magnet 41, conductor 53, contact 34², conductor 59 to conductor 57 and energy source 42, a second branch of the circuit going through conductor 53 and magnet 40, conductor 15 60, contact 34', joining the first branch at conductor 59 to conductor 57 and potentiometer energy source 42. The closing of the contacts 34' and 34² by the reset relay, although momentary or for a limited time where delaying means is 20 employed as described, causes the re-closing of the stick circuits for the magnets 40 and 41 since the trip contact 46 is closed and maintained closed, and thus a persisting resetting operation is effected.
- 25 The third reset contact 34³ is employed for the circuit of the delaying means or slow release controller 31, which circuit corresponds to that heretofore traced for Fig. 2 and comprises similar parts including the conductor 30 connected to the plus side of the energy source, the controller 31, the conductor 32, the slow release magnet 28, conductor 33, the contact 34³, and conductor 35 back to the other side of the energy source.
- The use and operation of the system embodying my invention and the numerous advantages thereof will in the main be apparent from the above detailed description thereof. It will be further apparent that while I have shown and described my invention in the preferred forms, many 35 changes and modifications may be made in the structure disclosed without departing from the spirit of the invention, defined in the following claims.
- I claim:
- 45 1. In combination, vehicle carried apparatus, a vehicle carried inductor means operable for producing a resetting operation in said vehicle carried apparatus, and a single roadside inductor cooperating with said vehicle carried inductor means, said roadside inductor embodying a tuned circuit devoid of an energy source and operative when closed for affecting the vehicle carried inductor means to produce the resetting operation thereof.
- 50 2. In combination, vehicle carried apparatus including a source of energy, a vehicle carried inductor means including inductively coupled coils connected to said energy source and operable for producing a resetting operation in said vehicle carried apparatus, and a roadside inductor means cooperating with said vehicle carried inductor means, said roadside inductor means including an inductor coil and a tuned circuit therefor devoid of an energy source, said circuit being operative when closed for affecting the inductively coupled coils of the vehicle carried inductor means to produce the resetting operation thereof.
- 55 3. In combination, vehicle carried apparatus including an alternating current source of energy, a vehicle carried inductor means operating through said energy source and operable for producing a resetting operation in said vehicle carried apparatus, and a roadside inductor cooperat-
- 60 4. In combination, vehicle carried apparatus including an electrically operated device and an A. C. source of energy, a vehicle carried inductor means including inductively coupled coils, one coil of which is connected in circuit to the energy source, said circuit being tuned substantially to the frequency of the A. C. source and said coils being operable for producing a resetting operation in said device, and a roadside inductor cooperating with said vehicle carried inductor means, said roadside inductor embodying an inductor coil and a circuit therefor devoid of an energy source, said roadside circuit being also tuned substantially to the frequency of the energy source and being operative when closed for affecting the vehicle carried inductor means to produce the resetting operation thereof.
- 65 5. In combination, vehicle carried apparatus including a source of energy, a vehicle carried inductor means energized from said vehicle source of energy and operable for producing an energy resetting operation in said vehicle carried apparatus, and a single roadside inductor cooperating with said vehicle carried inductor means, said roadside inductor embodying a tuned circuit devoid of an energy source and operative when closed for changing the energy relations in the vehicle carried inductor means to produce the resetting operation thereof.
- 70 6. In combination, vehicle carried apparatus including an A. C. source of energy, a vehicle carried inductor means energized from said source of energy and operable for producing a resetting operation in said vehicle carried apparatus, and a single roadside inductor cooperating with said vehicle carried inductor means, said roadside inductor embodying a circuit devoid of an energy source and operative when closed for changing the phase relations of the current and voltage effective in said vehicle carried inductor means for producing the resetting operation thereof.
- 75 7. In combination, vehicle carried apparatus including an A. C. source of energy, a vehicle carried inductor means energized from said source of energy and operable for producing a resetting operation in said vehicle carried apparatus, and a roadside inductor cooperating with said vehicle carried inductor means, said roadside inductor embodying a circuit devoid of an energy source and operative when closed for changing the phase relations of the current and voltage effective in said vehicle carried inductor means for producing the resetting operation thereof.
- 80 8. In combination, vehicle carried apparatus including an A. C. source of energy, a vehicle carried inductor means energized from said source of energy and operable for producing a resetting operation in said vehicle carried apparatus, and a roadside inductor cooperating with said vehicle carried inductor means, said roadside inductor embodying a tuned circuit devoid of an energy source and made resonant substantially to the frequency of said energy source, said circuit being operative when closed for changing the phase relations of the current and voltage effective in said vehicle carried inductor means for producing the resetting operation thereof.
- 85 9. In combination, vehicle carried apparatus

including an A. C. source of energy, a vehicle carried inductor connected in circuit to said source of energy and operable for producing a resetting operation in said vehicle carried apparatus, said circuit being tuned, and a roadside inductor cooperating with said vehicle carried inductor means, said roadside inductor embodying a correspondingly tuned circuit devoid of an energy source and operative when closed for changing the phase relations of the current and voltage effective in said vehicle carried inductor means for producing the resetting operation thereof.

10. In combination, vehicle carried apparatus including an A. C. source of energy, a vehicle carried inductor means operating through said energy source and operable for normally holding said apparatus in a set condition, and a roadside inductor cooperating with the vehicle carried inductor means, said roadside inductor embodying 15 a tuned circuit devoid of an energy source and made resonant to substantially the frequency of said A. C. source, said circuit being selectively operable for producing either a tripping or resetting operating condition in said vehicle carried inductor means.

11. In combination, vehicle carried mechanism comprising an electrically operated device, a source of energy, and an inductor means operating through said source of energy for controlling 20 the operation of said device and operative to normally hold said device in a set or energized state, and roadside mechanism comprising a single roadside inductor cooperating with said vehicle carried inductor means, said roadside inductor embodying energyless tuned circuit means selectively operable for producing in the vehicle carried inductor correspondingly selective conditions for either tripping or resetting said electrically operating device.

12. In combination, vehicle carried mechanism comprising an electrically operated device, a source of energy, and an inductor means including inductively coupled coils operating through said source of energy for controlling the operation of said device and operative to normally hold said device in a set or energized state, and roadside mechanism comprising a roadside inductor cooperating with said vehicle carried inductor means, said roadside inductor embodying 45 an inductor coil and a tuned circuit therefor devoid of an energy source, said circuit being selectively operable for producing in the vehicle carried inductively coupled coils correspondingly selective conditions for either tripping or resetting said electrically operated device.

13. In combination, vehicle carried apparatus including an A. C. source of energy and a relay operable by phase changes, a vehicle carried inductor means energized from said source of energy and operative for normally holding said apparatus in a set condition, and a roadside inductor cooperating with the vehicle carried inductor means, said roadside inductor embodying a circuit devoid of an energy source and operative 60 when open for producing a tripping condition in said vehicle carried inductor means and operative when closed for changing the phase relations of the current and voltage effective in said vehicle carried inductor means for producing the resetting operating condition therein for operating said relay.

14. In combination, vehicle carried apparatus including an A. C. source of energy and a relay operable by phase changes, a vehicle carried inductor means energized from said source of en-

ergy and operative for normally holding said apparatus in a set condition, and a single roadside inductor cooperating with the vehicle carried inductor means, said roadside inductor embodying a circuit devoid of an energy source and operative when open for producing a tripping condition in said vehicle carried inductor means and operative when closed for changing the phase relations of the current and voltage effective in said vehicle carried inductor means for producing the resetting operating condition therein for operating said relay.

15. In combination, vehicle carried apparatus including an A. C. source of energy and a relay operable by phase changes, a vehicle carried inductor means comprising inductively coupled coils energized from said source of energy and operative for normally holding said apparatus in a set condition, and a single roadside inductor cooperating with the inductively coupled coils, said roadside inductor embodying a circuit devoid of an energy source and operative when open for producing a tripping condition in said vehicle carried inductor means and operative when closed for changing the phase relations of the current and voltage effective in said vehicle carried inductor means for producing the resetting operating condition therein for operating said relay.

16. In combination, vehicle carried apparatus including an A. C. source of energy, a vehicle carried inductor means including inductively coupled primary and secondary coils, the primary of which is connected in tuned circuit to said source of energy, said means being operative for normally holding said apparatus in a set condition, and a roadside inductor cooperating with the vehicle carried inductor means, said roadside inductor embodying a tuned circuit devoid of an energy source and operative when open for producing a tripping condition in said vehicle carried inductor means and operative when closed for changing the phase relations of the current and voltage effective in the primary coil of said vehicle carried inductor means for producing the resetting operating condition therein.

17. In combination, vehicle carried apparatus comprising an A. C. source of energy, an inductor connected in circuit to said source of energy, and a relay having field and armature coils arranged in said circuit; and roadside mechanism comprising a roadside inductor arranged to cooperate with the vehicle carried inductor and a circuit for said roadside inductor devoid of an energy source and operative when closed for affecting the vehicle carried inductor to produce an operation of the said relay.

18. In combination, vehicle carried apparatus comprising an A. C. source of energy, an inductor connected in circuit to said source of energy, and a relay having field and armature coils arranged in said circuit, the field and armature coils being respectively in series with and in parallel to said inductor, and roadside mechanism comprising a roadside inductor arranged to cooperate with the vehicle carried inductor and a circuit for said roadside inductor devoid of an energy source and operative when closed for affecting the vehicle carried inductor to produce an operation of the said relay.

19. In combination, vehicle carried apparatus comprising an A. C. source of energy, an inductor connected in circuit to said source of energy, and a relay having field and armature coils arranged in said circuit, the currents of the field and arma-

- ture coils being phased 90 electrical degrees apart to produce normally a no torque condition in said relay; and roadside mechanism comprising a roadside inductor arranged to cooperate with the vehicle carried inductor and a circuit for said roadside inductor devoid of an energy source and operative when closed for affecting the vehicle carried inductor to produce a phase shift of the currents in said field and armature coils
- 5 10 and a consequent operation of the said relay.
20. In combination, vehicle carried apparatus comprising an A. C. source of energy, an inductor connected in circuit to said source of energy, and a relay having field and armature coils controlled by said circuit, the currents of the field and armature coils being phased 90 electrical degrees apart to produce normally a no torque condition in said relay; and roadside mechanism comprising a roadside inductor arranged to cooperate with the vehicle carried inductor and a circuit for said roadside inductor devoid of an energy source and operative when closed for affecting the vehicle carried inductor to produce a phase shift of the currents in said field and armature coils
- 15 20 25 and a consequent operation of the said relay.
21. In combination, vehicle carried apparatus comprising an A. C. source of energy, an inductor connected in circuit to said source of energy, a two element relay controlled by said circuit, the quotient of the resistance and the reactance of said inductor being made substantially equal to the quotient of the circuit reactance and the resistance of one of the elements of said relay; and roadside mechanism comprising a roadside inductor arranged to cooperate with the vehicle carried inductor and a circuit for said roadside inductor operative when closed for affecting the vehicle carried inductor to produce an operation of the said relay.
- 30 35 40 45 50 55 60 65 70 75 80 85 90 95 100 105 110 115 120 125 130 135 140 145 150
22. In combination, vehicle carried apparatus comprising an A. C. source of energy, an inductor connected in circuit to said source of energy, and a relay having field and armature coils arranged in said circuit, the field and armature coils being respectively in series with and in parallel to said inductor, the quotient of the resistance and the reactance of said inductor being made substantially equal to the quotient of the armature circuit reactance and the armature circuit resistance; and roadside mechanism comprising a roadside inductor arranged to cooperate with the vehicle carried inductor and a circuit for said roadside inductor operative when closed for affecting the vehicle carried inductor to produce an operation of the said relay.
23. In combination, vehicle carried apparatus comprising an A. C. source of energy, an inductor connected in circuit to said source of energy, and a relay having field and armature coils arranged in said circuit, the field and armature coils being respectively in series with and in parallel to said inductor, the quotient of the resistance and the reactance of said inductor being made substantially equal to the quotient of the armature circuit reactance and the armature circuit resistance; and roadside mechanism comprising a roadside inductor arranged to cooperate with the vehicle carried inductor and a circuit for said roadside inductor devoid of an energy source and operative when closed for affecting the vehicle carried inductor to produce an operation of the said relay.
24. In combination, vehicle carried apparatus comprising an A. C. source of energy, an inductor connected in circuit to said source of energy, and a relay having field and armature coils arranged in said circuit, the field and armature coils being respectively in series with and in parallel to said inductor, the quotient of the resistance and the reactance of said inductor being made substantially equal to the quotient of the armature circuit reactance and the armature circuit resistance; and roadside mechanism comprising a roadside inductor arranged to cooperate with the vehicle carried inductor and a circuit for said roadside inductor devoid of an energy source and operative when closed for affecting the vehicle carried inductor to produce an operation of the said relay.
- 25 30 35 40 45 50 55 60 65 70 75 80 85 90 95 100 105 110 115 120 125 130 135 140 145 150
- in said circuit, said circuit being made resonant substantially to the frequency of said A. C. source; and roadside mechanism comprising a roadside inductor arranged to cooperate with the vehicle carried inductor and a circuit for said roadside inductor devoid of an energy source and operative when closed for affecting the vehicle carried inductor to produce an operation of the said relay.
26. In combination, vehicle carried apparatus comprising an A. C. source of energy, an inductor connected in circuit to said source of energy, and a relay having field and armature coils arranged in said circuit, said circuit being made resonant and having a resonant frequency somewhat higher than the frequency of the A. C. source; and roadside mechanism comprising a roadside inductor arranged to cooperate with the vehicle carried inductor and a circuit for said roadside inductor devoid of an energy source and operative when closed for affecting the vehicle carried inductor to produce an operation of the said relay.
27. In combination, vehicle carried apparatus comprising an A. C. source of energy, an inductor connected in circuit to said source of energy and a two-element relay in said circuit, one element of said relay being in series with and the other element of said relay being in parallel to the said inductor.
28. In combination, vehicle carried apparatus comprising an A. C. source of energy, an inductor connected in circuit to said source of energy, and a relay having field and armature coils arranged in said circuit, the field and armature coils being respectively in series with and in parallel to said inductor.
29. In combination, vehicle carried apparatus comprising an A. C. source of energy, an inductor connected in circuit to said source of energy, a two-element relay controlled by said circuit, one element of said relay being in series with and the other element of said relay being in parallel to the said inductor and the currents in said elements being normally phased 90 electrical degrees apart.
30. In combination, vehicle carried apparatus comprising an A. C. source of energy, an inductor connected in circuit to said source of energy, and a two-element relay controlled by said circuit, one element of said relay being in series with and the other element of said relay being in parallel to the said inductor, and the quotient of the resistance and the reactance of said inductor being substantially equal to the quotient of the circuit reactance and the resistance of the in parallel relay element.

31. In combination, vehicle carried apparatus comprising an A. C. source of energy, an inductor connected in circuit to said source of energy, and a two-element relay in said circuit, one element of said relay being in series with and the other element of said relay being in parallel to the said inductor, the said series circuit being made resonant to substantially the frequency of the A. C. source.
- 10 32. In combination, vehicle carried apparatus comprising an A. C. source of energy, an inductor connected in circuit to said source of energy and a two-element relay in said circuit, one element of said relay being in series with and the other element of said relay being in parallel to the said inductor, the said series circuit being tuned and made resonant to a frequency slightly higher than the frequency of the A. C. source.
- 15 33. In combination, vehicle carried apparatus comprising an A. C. source of energy, an inductor connected in circuit to said source of energy, and a relay having field and armature coils arranged in said circuit, the field and armature coils being respectively in series with and in parallel to said inductor, the quotient of the resistance and the reactance of said inductor being substantially equal to the quotient of the armature circuit reactance and the armature circuit resistance.
- 20 34. In combination, vehicle carried apparatus comprising an A. C. source of energy, an inductor connected in circuit to said source of energy, and a relay having field and armature coils arranged in said circuit, the field and armature coils being respectively in series with and in parallel to said inductor and the currents in said field and armature coils being normally phased 90 electrical degrees apart.
- 25 35. In combination, vehicle carried apparatus comprising an A. C. source of energy, an inductor connected in circuit to said source of energy, and a relay having field and armature coils arranged in said circuit, the field and armature coils being respectively in series with and in parallel to said inductor, the said series circuit being tuned and made resonant to a frequency slightly higher than the frequency of the A. C. source.
- 30 36. In combination, vehicle carrier apparatus comprising a source of energy, an inductor including inductively coupled coils the primary of which is connected to said source of energy, a trip relay connected to the secondary of said coils, and a reset relay connected to the primary of said coils; and roadside mechanism comprising a roadside inductor arranged to cooperate with the inductively coupled coils of the vehicle carried inductor and circuit means for said roadside inductor selectively operable for producing in said vehicle carried coupled coils either a condition to operate said trip relay or a condition to operate said reset relay.
- 35 37. In combination, vehicle carried apparatus comprising a source of energy, an inductor including inductively coupled coils the primary of which is connected to said source of energy, a relay connected to the secondary of said coils, and a second relay connected to the primary of said coils, the said second relay having a field coil in series with and an armature coil in parallel to the primary inductor coil; and roadside mechanism comprising a roadside inductor arranged to cooperate with the inductively coupled coils of the vehicle carried inductor and circuit means for said roadside inductor selectively operable for producing in said vehicle carried coupled coils either a condition to operate said trip relay or a condition to operate said reset relay.
- 40 38. In combination, vehicle carried apparatus comprising a source of energy, an inductor including inductively coupled coils the primary of which is connected to said source of energy, a trip relay connected to the secondary of said coils, and a reset relay connected to the primary of said coils; and roadside mechanism comprising a roadside inductor arranged to cooperate with the inductively coupled coils of the vehicle carried inductor and a circuit devoid of an energy source for said roadside inductor operable when open for producing in said vehicle carried coupled coils a condition to trip said trip relay and operable when closed for producing in the coupled coils a condition to reset said reset relay.
- 45 39. In combination, vehicle carried apparatus comprising a source of energy, an inductor including inductively coupled coils the primary of which is connected to said source of energy, a relay connected to the secondary of said coils, and a second relay connected to the primary of said coils; and roadside mechanism comprising a roadside inductor arranged to cooperate with the inductively coupled coils of the vehicle carried inductor and circuit means for said roadside inductor selectively operable for producing in said vehicle carried coupled coils either a condition to operate said first relay or a condition to operate said second relay.
- 50 40. In combination, vehicle carried apparatus comprising a source of energy, an inductor including inductively coupled coils the primary of which is connected to said source of energy, a trip relay connected to the secondary of said coils, and a reset relay connected to the primary of said coils, said reset relay having field and armature coils phased 90 electrical degrees apart; and roadside mechanism comprising a roadside inductor arranged to cooperate with the inductively coupled coils of the vehicle carried inductor and a circuit for said roadside inductor selectively operable for producing in said vehicle carried coupled coils either a condition to trip said trip relay or a condition to change the phase relations in the relay field and armature coils to operate said reset relay.
- 55 41. In combination, vehicle carried apparatus comprising a source of energy, an inductor including inductively coupled coils the primary of which is connected in circuit to said source of energy, a trip relay connected in circuit to the secondary of said coils, and a reset relay connected to the primary of said coils, the primary circuit being tuned to a resonant frequency somewhat higher than the frequency of said A. C. source and the secondary circuit being tuned to a frequency somewhat lower than the frequency of said A. C. source; and roadside mechanism comprising a roadside inductor arranged to cooperate with the inductively coupled coils of the vehicle carried inductor and circuit means for said roadside inductor selectively operable for producing in said vehicle carried coupled coils either a condition to operate said trip relay or a condition to operate said reset relay.
- 60 42. In combination, vehicle carried apparatus comprising a source of energy, an inductor including inductively coupled coils the primary of which is connected to said source of energy, a trip relay connected in circuit to the secondary of said coils, and a reset relay connected in circuit to the primary of said coils, the said second relay having a field coil in series with and an armature coil in parallel to the primary inductor coil; the primary

- circuit being tuned to a resonant frequency somewhat higher than the frequency of said A. C. source and the secondary circuit being tuned to a frequency somewhat lower than the frequency of said A. C. energy source. 5
43. In combination, vehicle carried apparatus comprising a source of energy, an inductor including inductively coupled coils the primary of which is connected to said source of energy, a trip relay connected in circuit to the secondary of said coils, and a reset relay connected in circuit to the primary of said coils, the primary circuit being tuned to a resonant frequency somewhat higher than the frequency of said A. C. source and the secondary circuit being tuned to a frequency somewhat lower than the frequency of said A. C. energy source. 10
44. In combination, vehicle carried apparatus comprising a source of energy, an inductor including inductively coupled coils the primary of which is connected to said source of energy, a relay connected in circuit to the secondary of said coils, and a second relay connected in circuit to the primary of said coils, the primary circuit being resonant to substantially the frequency of said source of energy. 15
45. In combination, vehicle carried apparatus comprising a source of energy, an inductor including inductively coupled coils the primary of which is connected to said source of energy, a relay connected in circuit to the secondary of said coils, and a second relay connected in circuit to the primary of said coils, the secondary circuit being made resonant to substantially the frequency of said source of energy. 20
46. In combination, vehicle carried apparatus comprising a source of energy, an inductor including inductively coupled coils the primary of which is connected to said source of energy, a relay connected in circuit to the secondary of said coils, and a second relay connected in circuit to the primary of said coils, said second relay having field and armature coils phased 90 electrical degrees apart. 25
47. In combination, vehicle carried apparatus comprising a source of energy, an inductor including inductively coupled coils the primary of which is connected to said source of energy, a relay connected in circuit to the secondary of said coils, and a second relay connected in circuit to the primary of said coils, the said second relay having a field coil in series with and an armature coil in parallel to the primary coil, and the quotient of the resistance and reactance of said primary coil being made substantially equal to the quotient of 30 the armature circuit reactance and the armature circuit resistance. 55
48. In combination, vehicle carried apparatus, a vehicle carried inductor means operable for producing a resetting operation in said vehicle carried apparatus, and a single roadside inductor cooperating with said vehicle carried inductor means, said roadside inductor embodying a circuit devoid of an energy source and operative when closed for affecting the vehicle carried inductor means to produce the resetting operation thereof, during the time of cooperation between the vehicle carried inductor means and said roadside inductor; and means for delaying the release of said resetting operation. 60
49. In combination, vehicle carried apparatus comprising an A. C. source of energy, an inductor connected in circuit to said source of energy, a relay having field and armature coils arranged in said circuit, and a release delaying means for said relay; and roadside mechanism comprising 65
- a roadside inductor arranged to cooperate with the vehicle carried inductor and a circuit for said roadside inductor devoid of an energy source and operative when closed for affecting the vehicle carried inductor to produce an operation of the said relay. 80
50. In combination, vehicle carried apparatus comprising an A. C. source of energy, an inductor connected in circuit to said source of energy and a two-element relay in said circuit, one element of said relay being in series with and the other element of said relay being in parallel to the said inductor, and a release delaying means for said relay. 85
51. In combination, vehicle carried apparatus comprising a source of energy, an inductor including inductively coupled coils the primary of which is connected to said source of energy, a trip relay connected to the secondary of said coils, a reset relay connected to the primary of said coils and a release delaying means for said reset relay; and roadside mechanism comprising a roadside inductor arranged to cooperate with the inductively coupled coils of the vehicle carried inductor and circuit means for said roadside inductor selectively operable for producing in said vehicle carried coupled coils either a condition to operate said trip relay or a condition to operate said reset relay. 90
52. In combination, vehicle carried apparatus including an A. C. source of energy, a vehicle carried inductor means energized from said source of energy and operable for producing an operation in said vehicle carried apparatus, and a single roadside inductor cooperating with said vehicle carried inductor means, said roadside inductor embodying a circuit devoid of an energy source and operative when closed for changing the phase relations of the current and voltage effective in said vehicle carried inductor means for producing the said operation thereof. 105
53. In combination, vehicle carried apparatus including an A. C. source of energy, a vehicle carried inductor connected in circuit to said source of energy and operable for producing an operation in said vehicle carried apparatus, said circuit being tuned, and a roadside inductor cooperating with said vehicle carried inductor means, said roadside inductor embodying a correspondingly tuned circuit devoid of an energy source and operative when closed for changing the phase relations of the current and voltage effective in said vehicle carried inductor means for producing the said operation thereof. 110
54. In combination, vehicle carried apparatus including an A. C. source of energy, a vehicle carried inductor means comprising inductively coupled coils energized from said source of energy and operative for controlling said vehicle carried apparatus, and a single roadside inductor cooperating with the inductively coupled coils, said roadside inductor embodying a circuit devoid of an energy source and operative when open for producing a tripping condition in said vehicle carried inductor means and operative when closed for changing the phase relations of the current and voltage effective in said vehicle carried inductor means for producing another operation in said apparatus. 130
55. In combination, vehicle carried apparatus comprising an alternating current source of energy, an inductor including inductively coupled coils, the primary coil of which is connected in circuit to said source of energy and the secondary coil of which is wholly energized from said pri- 145
- 150

mary coil, and a relay in said primary circuit; and means for affecting said coils to operate said relay.

56. In combination, vehicle carried apparatus comprising an alternating current source of energy, an inductor including inductively coupled coils, the primary of which is connected in circuit to said source of energy and the secondary of which is energized wholly from said primary, and 10 a relay in said primary circuit; and means for operating said relay by producing a power change in said inductor.

57. In combination, vehicle carried apparatus comprising a source of energy, an inductor connected in circuit to said source of energy and a relay in said circuit; and roadside mechanism comprising a roadside inductor arranged to cooperate with the vehicle carried inductor and a tuned circuit for said roadside inductor devoid 20 of an energy source and operative when closed for affecting the vehicle carried inductor to operate said relay.

58. In combination, vehicle carried apparatus comprising a source of energy, an inductor including inductively coupled coils, the primary of which is connected in circuit to said source of energy, and a relay in said circuit; and roadside mechanism comprising a roadside inductor arranged to cooperate with the vehicle carried inductor and a circuit for said roadside inductor devoid of an energy source and operative when closed for affecting said vehicle carried inductor to operate said relay.

59. In combination, vehicle carried apparatus comprising a source of energy, an inductor connected in circuit to said source of energy and a relay in said circuit; and roadside mechanism comprising a roadside inductor arranged to cooperate with the vehicle carried inductor and a circuit for said roadside inductor devoid of an energy source and operative when closed for producing a power change in the vehicle carried inductor to operate said relay.

60. In combination, an inductor including inductively coupled primary and secondary coils, a relay connected in circuit to said primary coil, a second relay connected in circuit to said secondary coil, and means for influencing said inductor to selectively operate said relays.

61. In combination, an inductor including inductively coupled primary and secondary coils, a reset operating relay connected in circuit to said primary coil, a trip operating relay connected in circuit to said secondary coil, and means for influencing said inductor to selectively operate said relays.

62. In combination, vehicle carried apparatus including an inductor including inductively coupled primary and secondary coils, a relay connected in circuit to said primary coil, a second relay connected in circuit to said secondary coil, and means for influencing said inductor to selectively operate said relays.

63. In combination, an inductor including inductively coupled primary and secondary coils, a relay connected in circuit to said primary coil, a second relay connected in circuit to said secondary coil, and roadside inductor means for influencing said inductor to selectively operate said relays.

64. In combination, an inductor including inductively coupled primary and secondary coils, a relay connected in a tuned circuit to said primary coil, a second relay connected in a tuned circuit to

said secondary coil, and means for influencing said inductor to selectively operate said relays.

65. In combination, vehicle carried apparatus comprising an inductor, a trip relay connected in circuit to said inductor, a reset relay connected in circuit to said inductor and roadside apparatus including an inductor operative for influencing the vehicle carried inductor for selectively operating said trip and reset relays.

66. In combination, vehicle carried apparatus comprising an inductor, a trip relay connected in circuit to said inductor, a reset relay connected in circuit to said inductor and roadside apparatus including an inductor having a circuit devoid of an energy source operative for influencing the vehicle carried inductor for selectively operating said trip and reset relays.

67. In combination, vehicle carried apparatus comprising an inductor, a trip relay connected in a tuned circuit to said inductor, a reset relay connected in a tuned circuit to said inductor and roadside apparatus including an inductor operative for influencing the vehicle carried inductor for selectively operating said trip and reset relays.

68. An induction train control system comprising vehicle carried apparatus, a vehicle carried inductor means including an energy transmitting element and an energy receiving element coupled together and operative for tripping and resetting the vehicle carried apparatus, the tripping being effected upon a reduction of transmission of energy between the coupled elements, and roadside inductor means cooperating with the vehicle carried inductor means and comprising a single inductor element cooperable inductively with the vehicle carried coupled elements and circuit means devoid of any energy source governing said single inductor element for selectively producing therein tripping and resetting indications to selectively effect tripping and resetting operations of the vehicle carried inductor means.

69. An induction train control system comprising a controlling relay, a vehicle carried inductor means including an energy transmitting element and an energy receiving element coupled together, said energy receiving element being connected to said controlling relay and said elements being operative for tripping and resetting the controlling relay, the tripping being effected by substantially deenergizing said relay, and roadside inductor means cooperating with the vehicle carried inductor means and comprising a single inductor element cooperable inductively with the vehicle carried coupled elements and circuit means devoid of an energy source governing said single inductor element for selectively producing therein tripping and resetting indications to selectively effect tripping and resetting operations of the vehicle carried inductor means.

70. An induction train control system comprising vehicle carried apparatus, a vehicle carried inductor means including an energy transmitting element and an energy receiving element coupled together and operative for tripping and resetting the vehicle carried apparatus, a roadside inductor means cooperating with the vehicle carried inductor means and comprising a single inductor element cooperable inductively with the vehicle carried coupled elements and capable when in effectively open circuit of reducing the transmission of energy from said energy transmitting element to said energy receiving element to produce a tripping operation in said vehicle carried apparatus, and circuit means devoid of an energy source governing the said inductor element for

producing therein a resetting indication transmittable to for effecting a resetting operation of said vehicle carried inductor means.

71. An induction train control system comprising a governing relay, a vehicle carried inductor means including an energy transmitting element and an energy receiving element coupled together, said energy receiving element being connected to said controlling relay and said elements being operative for tripping and resetting the said relay, a roadside inductor means cooperating with the vehicle carried inductor means and comprising

a single inductor element cooperable inductively with the vehicle carried coupled elements and capable when in effectively open circuit of influencing said vehicle carried inductor means to produce a tripping deenergization of said relay, and circuit means devoid of an energy source governing the said roadside inductor element for producing therein a condition transmittable to said vehicle carried inductor means for effecting a resetting operation of said relay. 80 85
